CLAIM

The ornamental design for a weed trimmer head spool with angled guide channel, as shown and described.

DESCRIPTION

FIG. 1 is a perspective view of a weed trimmer head spool with angled guide channel showing my new design;

FIG. 2 is a front elevational view thereof with the rear elevational being a mirror image thereof;

FIG. 3 is a cross-sectional view taken along lines 3-3 of FIG. 2;

FIG. 4 is a right side elevational view with the left side being a mirror image thereof;

FIG. 5 is a top view thereof;

FIG. 6 is a bottom view thereof; and,

FIG. 7 is a cross-sectional view taken along lines 7-7 of FIG. 5.
